UNITED STATES PATENT OFFICE

170,098

MAGAZINE RACK

Keith N. Swanson, Santa Barbara, Calif.

Application February 16, 1953, Serial No. 23,624

Term of patent 14 years

(CL. D33—2)

To all whom it may concern:

Be it known that I, Keith N. Swanson, a citizen of the United States, residing at 1106A Garden Street, Santa Barbara, in the county of Santa Barbara, State of California, have invented a new, original, and ornamental Design for a Magazine Rack, of which the following is a specification, reference being had to the accompanying drawing, forming a part thereof.

Fig. 1 is a perspective view of a magazine rack embodying my new design;

Fig. 2 is a front elevational view;

Fig. 3 is a side elevational view; and

Fig. 4 is a bottom plan view.

I claim:

The ornamental design for a magazine rack, as shown.

KEITH N. SWANSON.
